R. F. Burns

ATTORNEY

UNITED STATES PATENT OFFICE.

ISIDOR NEWMAN, OF NEW YORK, N. Y.

KEY HOLDER.

Application filed April 10, 1926. Serial No. 101,036.

My invention relates to improvements in key holders adapted to retain several keys to be carried in a person's pocket, and is particularly applicable to the class of key holders in which individual keys are retained side by side within a foldable cover or case.

The object of my invention is to provide means to movably retain keys in such a way that they may be turned into various positions and be rotated axially while the cover is retained in the hand to facilitate the operation of the keys in locking and unlocking doors and the like, and whereby the keys may all be retained in proper position within the folded cover or case for carrying.

In carrying out my invention I provide a support having a pin or bar upon which heads are pivotally supported and within the heads disks are supported to rotate, which disks are provided with loops that extend through openings in the heads, whereby the disks may rotate in the heads, and key-holding members or hooks are freely connected with the loops so that said members may move into various positions on the loops beyond the heads, whereby the keys are free to move in various directions, as well as to rotate axially for use. The support is adapted to be attached to a foldable cover or case, such as a piece of leather or the like, to enclose the keys in an ordinary way for carrying the keys snugly.

My invention comprises novel details of improvement that will be more fully herein-after set forth and then pointed out in the claims.

Reference is to be had to the accompanying drawings forming a part hereof, wherein

Fig. 1 is a detail view on an enlarged scale of a key holder embodying my invention;

Fig. 2 is a section on line 2, 2, in Fig. 1;

Fig. 3 is a substantially similar view illustrating a key in a different position;

Fig. 4 is a detail section on line 4, 4, in Fig. 2;

Fig. 5 illustrates the head and disk of the key holder detached in perspective; and

Fig. 6 is an end view of the key holder folded for carrying the keys.

Similar numerals of reference indicate corresponding parts in the several views.

The support 1 is shown in the form of a plate having spaced eyes or loops 2 coiled from the metal of the plate, which may be done by suitably cutting prongs or projec-

tions at the edge of the support, in which eyes a bar or rod 3 is secured. Spaces are provided at 4 between the eyes 2. At 5 are heads which have spaced lugs 6 provided with holes 7 that receive the rod 3, whereby the heads are journaled on the rod to rotate back and forth thereon, with an eye 2 between two lugs. The spaced lugs provide substantial strength to resist strains. The heads 5 are hollow and are provided with openings 5^a in their transverse end portions 5^b, whereby inwardly extending flanges 5' are formed around said openings. At 8 are disks journaled within the heads 5 against the end flanges 5', which disks are provided with outwardly projecting loops 9 that extend through the openings 5^a of the heads 5. The disk 8 and its loop 9 are formed integrally in a single piece of metal, providing strength to prevent the parts from being pulled apart during use. The openings 5^a in the heads are wider than the loops which permits the loops to be readily inserted between the lugs 6 and through said openings, with the integral disks abutting the flanges 5', the disks being of greater diameter than the loops and the openings, which flanges prevent the disks from being pulled through the openings and rotatively retain the disks, the edges of the disks being guided by the flange portions 5^c of the heads, whereby the loops may rotate completely around. At 10 are key retaining members or hooks, the inner loop-like ends of which are attached to the loops 9 of the disks 8 and are free within such loops, being retained therein by the heads 5 so that the members may swing freely in various directions relatively to the loops. With the members 10 in the loops 9 and against the heads 5 the disks 8 are rotatively retained in the heads 5, the disks also opposing the eyes 2. The keys 11 may be attached to the members 10 as illustrated by means of holes or eyes in the keys.

The support 1 may be attached to any desired cover or case 12, as by means of rivets 13. I have illustrated a cover or case of an ordinary form which may be of leather or other suitable material and is shown of the variety having a main portion to which the support 1 is attached and foldable portions 13^a, 13^b to be folded over the enclosed keys and adapted to be retained closed by complementary snap fasteners, buttons or the like, indicated generally at 14.

By means of my improvement the keys

are movably supported so as not only to have individual motion on the loop-like members 10 but such members and the keys may be moved into various angular positions respecting the cover or casing, and by reason of the journaling of the disks 8 within the heads 5 the keys may be rotated within a lock while the cover or case is held stationary in the hand, thereby facilitating the use of 10 the device.

Having now described my invention what I claim is:—

1. A key retainer comprising a bar, supporting means for the bar, heads journaled 15 to rotate upon the bar and provided with end openings, disks journaled within the heads and having loops projecting through said openings, the openings in the heads being wider than the loops to permit the latter 20 to be pushed through the openings, the heads having inwardly extending flanges at the openings, the disks being of greater diameter than the openings and the loops and opposing the flanges to rotatively retain the 25 disks on the heads and prevent the disks from being pulled through the openings, and key retaining members movably connected with the loops, whereby the heads and the keys may swing on the bar as an 30 axis, the disks and the keys may be rotated axially and the members with the keys may swivel on the loops when the device is retained in the hand.
2. A key retainer comprising a bar, heads 35 having spaced lugs journaled upon the bar and provided with end openings, the heads having inwardly extending flanges around said openings, disks journaled within the heads and having integral loops extending 40 through the openings and beyond the heads, the heads being of greater diameter than the openings and the loops and opposing the flanges to prevent the disks from being pulled through the openings and for rotation 45 relatively to the heads, and key retaining members loosely hung upon loops beyond the heads, whereby the members and the keys may swing in various positions and the disks with the keys may rotate axially when the device is held in the hand.
3. A key retainer comprising a support

provided with spaced eyes, a rod extending within said eyes and through the spaces between the eyes, heads having spaced lugs journaled upon the rod on opposite sides of a corresponding eye, the eye keeping the head in operative position on the rod, the heads having side flanges and openings in their end portions, disks journaled within the heads and guided for rotation by the 60 said flanges, said disks having loops extending through said openings adapted to rotate therein, and key retaining members journaled loosely upon said loops, whereby the heads may rotate on the rod and the disks 65 with the retaining members and the keys may rotate relatively to the heads and the members may swing into various positions relatively to the heads.

4. A key retainer comprising a plate provided with spaced eyes at an edge, a bar in said eyes, a foldable case to which the plate is secured with the bar adjacent to one edge of the case, heads having apertured lugs journaled upon the rod, an eye of the support being located between the lugs of a head, the eye keeping the head in operative position on the rod, the heads having openings, disks journaled within the heads and provided with loops extending through the 75 openings, and key retaining members loosely supported upon the loops, whereby the heads may rotate within and without the case and the disks may rotate within the heads, the key retaining members being adapted 80 to swing in various directions upon the loops.

5. In a key retainer a head having an opening at one end and having an inwardly extending flange around said opening, a disk journaled within the head and opposing the flange, the disk being provided with an outwardly extending loop integral therewith, the opening being wider than the loop to permit the latter to be passed therethrough 90 to locate the disk against the flange, and a key retaining member movably connected with the loop on the side of the head opposite the disk, whereby the disk and the key may be rotated axially and the member with 95 the key may swivel on the loop.

ISIDOR NEWMAN.
